UNITED STATES PATENT OFFICE.

OVERTON WINSTON, OF MINNEAPOLIS, MINNESOTA.

HEADLIGHT.

1,279,061.

Specification of Letters Patent. Patented Sept. 17, 1918.

Application filed March 27, 1916. Serial No. 86,852.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights for automobiles and other vehicles, and more particularly to headlights where- 15 in double filament electric light bulbs are employed. Generally stated, the invention consists of the novel devices and combinations of devices hereinafter described and defined in the claims.

20 In the accompanying drawings which illustrate the invention, like characters indicate like parts throughout the several views.

Referring to the drawings:

Figure 1 is a vertical section taken centrally through a headlight embodying my invention;

Fig. 2 is a diagrammatic view illustrating the wires of the electric lamp;

Fig. 3 is a transverse section taken on the line $\alpha^3 \alpha^3$ of Fig. 1;

Fig. 4 is a rear end elevation of the shank or sleeve portion of the electric lamp;

Fig. 5 is a front end elevation showing one of the shells or sections of the lamp socket and its adjustable lamp holding collar; and

Fig. 6 is an axial section of the eccentric lamp holding collar.

The numeral 1 indicates the case of an ordinary headlight, such as used on automobiles. The numerals 2 and 3 indicate, respectively, the reflector and the lens or glass plate of the headlight. The electric light bulb 4 is of the two filament type, and involves novel features in the arrangement of its filaments. The said filaments designated at 5 and 5^a are formed as a continuous filament, the ends thereof being connected to electrodes 6 and 7 and the intermediate portion thereof being connected to a central electrode 8.

In the electric connections shown, the so-called electrodes 6, 7 and 8 are directly connected to the wires 6^a, 7^a and 8^a, respectively, in the shank of the bulb, and the said wires are adapted to be connected, respectively,

to circuit wires 6^b, 7^b, and 8^b, through contacts which will now be described.

The wire 6^a is connected to an axially located contact 9; the wire 7^a is connected to a contact ring 10 and the wire 8^a is connected to the contact sleeve 11. The sleeve 11 surrounds the shank of the bulb in the usual way and the said contacts 11, 9 and 10 are concentrically located and insulated, one 65 from the other. The numeral 12 indicates a battery or other source of electrical energy, one side of which is connected to the lead wire 8^b and the other side of which is connected by a wire 13 to a switch 14 which 70 is adapted to make connection with terminal contacts of the lead wires 6^b and 7^b, at will. The contacts on the lamp socket which engage with the above described contacts 9, 10 and 11 on the lamp will be described after 75 having first described the construction of the said lamp socket.

The lamp socket comprises two telescoping cylindrical shells 15 and 16 and a lamp holding collar 17. The outer shell 15 is 80 shown as screw-threaded into the sleeve-like hub of an annular anchor plate 18 that is soldered, welded, or otherwise rigidly secured to the back of a reflector immediately surrounding an annular passage provided 85 in the latter for clearance of the said sleeve 16. The inner shell 16 is held for sliding movements, but against rotary movements within the shell 15, as shown, by means of a key lug 19 on said inner shell that works 90 in a longitudinal slot 20 in said outer shell. The holding collar 17 has an eccentric flange 21 that is swiveled in the front end of the inner shell 16.

Rigidly secured within the inner shell 16 95 is an insulating block 22 that has a rigidly secured rearwardly projected axial stem 23 and a forwardly spring-pressed contact stem 24 that is rectangular in cross section, and hence, cannot rotate in respect to the said 100 block. The threaded stem 23 works with threaded engagement in a tubular shaft 25 that is provided at its front end with disk-like head 26 swiveled in the extreme rear end of the outer shell 15. The shaft 25 projects axially through a bearing 1^a on the back of the lamp casing 1, and terminates in a knurled head 27 by means of which it may be easily rotated. A light spring finger 28 anchored on the bearing 1^a engages the 110 head 27 to hold the shaft 25 against accidental rotation. The numeral 29 indicates

a detachable cap which, as shown, covers the head 27 and is screwed onto the hub of the bearing 1^a.

The above noted stems 23 and 24 are insulated, one from the other, and on the said contact stem 24 is a slidible non-rotary insulating disk or contact carrier 30. On the front face of this contact carrier 30 is a divided electric contact 31, which, however, 10 operates as a single contact.

The above noted circuit lead wire 6^b is connected to the axial contact stem 24, while the lead or wire 7^b is connected to the divided contact 31.

15 The lamp sleeve 11 is provided with a plurality, as shown, with two outwardly projecting lock lugs or studs 32 that are adapted to be passed through internal grooves 33 in the collar 17 and then, by rotation of the 20 lamp, to be engaged with a corrugated or serrated shoulder 34 formed in the said collar 17 at the inner extremities of the said grooves 33.

When the lamp is inserted into the holding collar 17 of the socket, and its lugs 32 are engaged with the corrugations 34, such engagement will be yeldingly maintained by the forwardly spring-pressed contacts 24 and 31. When the lamp is rotated while its lugs

30 are thus engaged with the said corrugations, the eccentric 21 will be rotated with the lamp and the hot spot of the filament 5^a may be adjusted through a circle that will carry it toward and from the axis of the reflector.

35 When, however, the lamp is pressed rearward and then rotated, the collar 17 will not be rotated, but the lamp will rotate within the said collar, and by such adjustments, the two filaments 5 and 5^a may be properly set in

40 the same vertical plane, that is, the latter directly over the former. If the lamp be pressed rearward and then held against rotation, the collar 17 then may be rotated and the lamp adjusted in a plane transversely of 45 the axis of the reflector without changing the position of the filaments, in respect to a vertical position. By these compound rotary adjustments of the lamp and collar, the hot spot of the main or relatively high power

50 filament 5 may be always properly set in respect to the axis of the reflector. To set the lamp filament at the focal center of the reflector, the adjusting shaft 25 is rotated, thereby moving the inner shell 16, adjusting collar 17 and lamp bulb axially of the reflector until the desired adjustment is accomplished.

The two filament light bulb involves novel construction in the arrangement of its filaments, and its novel relative arrangement of circuit connections therefor, but these are features not herein claimed, but which are made the subject matter of a companion application, S. N. 169,203, filed of date May 17, 65 1917, and entitled Headlights.

What I claim is:

1. The combination with a reflector and a coöperating socket, of an electric light bulb rotatively adjustable in said socket, having interlocking engagement therewith and arranged to be operatively set and electrically connected in different rotary adjustments, said bulb having two filaments, one at the axis and the other radially offset from the axis of said reflector. 70 75

2. The combination with a reflector, and a socket located axially thereof, of an electric light bulb rotatively adjustable in said socket, having interlocking engagement therewith and arranged to be operatively set 80 in different rotary positions, said bulb having two diametrically extended filaments, one at the axis and the other radially offset from the axis of said reflector, said bulb, on its shank, having three radially spaced contacts electrically connected to said two filaments and said socket having three radially spaced electrical contacts coöperating with the electrical contacts of said bulb and arranged to maintain circuits through said 90 filaments in the various rotary adjustments of said bulb, the contacts of said bulb being movable over the contacts of said socket, when said bulb is rotatively adjusted. 85

3. The combination with a reflector and a coöperating socket, of a holding collar rotatively adjustable in said socket, an electric light bulb having interlocking engagement with said collar and arranged to be operatively set and electrically connected in different rotary adjustments therein; said bulb having two filaments, one at the axis and the other radially offset from the axis of said reflector. 100

4. The combination with a reflector and a coöperating socket, an eccentric holding collar rotatively adjustable in said socket, and an electric light bulb having interlocking engagement with said collar and arranged to be operatively set and electrically connected 105 in different rotary adjustments in respect to said collar, said bulb having two filaments, one at the axis and the other radially offset from the axis of said reflector. 110

5. The combination with a reflector, of a lamp socket comprising telescopic sections, one of which is fixed and the other of which is axially movable, an insulating body within the said movable section, an angular contact stem projecting axially forward from said insulating body, a non-rotary insulating disk slidible on said contact stem, an electric contact on said disk, an electric circuit having one lead connected to said contact stem, one to the contact on said insulating disk and the other to the metallic body of said socket, and a two-filament lamp supported by said socket and provided with three concentric contacts, one engageable with said contact stem, one with the contact on said insulating 120 125 130

disk and the other electrically connected to the metallic body of said socket.

6. The combination with a reflector, of a lamp socket comprising a positively fixed outer shell, an inner shell adjustable axially within said outer shell, an eccentric sleeve swiveled in the end of said inner shell and adjustable axially therewith.

7. The combination with a reflector, of a lamp socket comprising a positively fixed outer shell, an inner shell adjustable axially within said outer shell, an eccentric sleeve swiveled in the end of said inner shell and

adjustable axially therewith, a threaded stem fixed in respect to said inner shell, and an adjusting shaft swiveled to said outer shell and having threaded engagement with said threaded stem for adjusting said inner shell and parts carried therewith axially of the reflector.

In testimony whereof I affix my signature in presence of two witnesses.

20
OVERTON WINSTON.
